W. H. PECK

CENTRIFUGAL SEPARATOR

Original Filed March 2, 1922.

Wilbur H. Peck

UNITED STATES PATENT OFFICE.

WILBUR H. PECK, OF LOS ANGELES, CALIFORNIA.

CENTRIFUGAL SEPARATOR.

Application filed March 2, 1922, Serial No. 540,462. Renewed June 21, 1924.

To all whom it may concern:

Be it known that I, WILBUR H. PECK, a citizen of the United States, residing in the city of Los Angeles, Los Angeles County, 5 State of California, have invented certain new and useful Improvements in Centrifugal Separators, of which the following is a specification.

My invention relates to devices for 10 separation of materials of different degrees of specific gravity and compositions, more especially mineral containing substances, while in a finely divided state, and mixed with water, wherein centrifugal force, co- 15 ordinating with resisting liquid currents are used to effect such separation.

The main objects of my invention are to 20 create a separator of an economical and highly practicable character and with high efficiency in effecting the separation desired, and I accomplish these objects by the means and mechanism herein below described and illustrated in the accompanying drawings, in which:

25 Fig. 1 is partly a side elevation and partly a vertical central section of my centrifugal separator, also showing some parts broken away.

Fig. 2 is partly a front end elevation and 30 partly a cross section of my separator, especially showing the relative assemblage of the central or rotatable parts and the inner construction of some of such parts.

Fig. 3 is a top plan of one of the separating members detached and enlarged.

Fig. 4 is a vertical longitudinal section of 35 a separating member taken on line 4—4 of Fig. 3 looking in the direction of the arrow.

Fig. 5 is a detached and enlarged longitudinal central section of one of the discharge nipples or separating members through which the coarser material is discharged.

40 In making my improved centrifugal separator I provide a central rotatable receiving member 2, which I prefer to form as a comparatively short tube shaped bowl or drum of appropriate dimensions.

45 This receiving member is shown partly in side elevation and partly in central longitudinal sections in Fig. 1, and partly in cross section, and partly indicated in front elevation by dotted lines in Fig. 2. It is preferably made of metal turned true and con-

centric, adapted to high speed of rotation. It is provided with an internal receiving chamber 2', and at its bottom or inner end has a central hub 3, by which it is rigidly and concentrically mounted on a horizontal 60 shaft 4.

The shaft is journaled in boxes 5 and 6, which are carried on the upper ends of stands 7 and 8, which in turn are mounted on a base plate 9, of the separator. The 65 shaft may be rotated as desired by a pulley 10, from any suitable source of power, and carries with it in rotation the receiving member 2.

Secured on the outer circumference of the 70 receiving member in position extending out radially are mounted multiple separating members 11, which are preferably curved at their points of contact with the receiving member, as shown in Figs. 2 and 4, so these 75 portions of the separating members will conform to the curvature of the outer circumference of the receiving member and fit evenly and tightly thereon.

The members 11, are provided with 80 appropriate flanges 12, through which they are secured by the receiving member, as shown in Figs. 1 and 2, by screw bolt 13. They have open tops when removed, as especially shown in Figs. 3 and 4. 85

To serve as one head for closure of the receiving member to the extent desired, and to assist in forming a comparatively even exterior to the rotatable receiving and separating members, as well as to assist in 90 maintaining the separating members in place while under centrifugal stress during operation, I provide a metal disc or plate 14, which is secured to the end of the receiving member by the screw bolt 15. 95

There is also a metal plate 16, mounted on the other end of the receiving member, which, with the plate 14, assists in effecting more even contour of the rotating parts, as well as assisting in maintaining the 100 separating members in place by engaging trunnions or projections 17, as illustrated, which are rigidly secured to the sides of the separating members.

To further effect as nearly as practicable, 105 a comparatively even exterior surface to the assembled rotatable parts of the separator, thereby reducing friction in operation and reducing air currents generated in rotation, also inuring to greater safety, I provide a 110

peripheral band or covering 18, which is preferably carried by the circumferential edges of the plates 14 and 16.

The separating members are provided 5 with separating chambers 19, preferably contracting in size in direction from the axis of rotation, and there is preferably provided within these chambers a desired number of partitions or baffles 20, fixed with respect to 10 the separating members, which I will term separating baffles, extending between the side walls of the separating members transversely to the course of rotation.

These baffles are preferably comparatively 15 wide and thin and positioned radially edge-ways, with their inner edges far enough from the outer circumference of the receiving member to leave comparatively small desired space between them and such circumference, for flow of parts of the separated pulp, while the outer edges extend out only 20 part way to the discharge passages of the separating chamber, as illustrated.

During operation the separating chamber 25 being full of pulp, the coarser and un-separated portion of the pulp in transit through the separating chamber will flow across adjacent to the outer edges of these baffles, and the finer parts of the pulp, as 30 the same is separated, will flow inwardly between the separating baffles and across or adjacent to their inner edges, and over the inner edge of a discharge baffle or partition 21, into the discharge chamber 22.

In addition to the separating baffles 20, I 35 provide a baffle or partition 23, which I will term a feed baffle, also positioned in the separating chamber transversely to the course of rotation, and with its inner edges 40 contacting tightly with the outer circumference of the receiving member so that pulp will not flow between these parts.

This feed baffle extends outward preferably about the same distance as the separating 45 baffles 20, and forms with the wall of the separating member a passage 24, which I will term a feed chamber, for receiving and guiding flow of pulp from the receiving member, into the separating chamber, within 50 the zone of the outer edges of the separating baffles. The finer of such pulp from there, flows up between the separating baffles and over the edge of the discharge baffle 21, into the discharge chamber 22, and to discharge 55 through the discharge openings 25, which are indicated in dotted lines, as hereinafter more fully explained. The pulp passes from the receiving chamber 2', into the feed passage, through openings 26, in 60 the wall of the receiving member.

During this time, the separated coarse parts of the pulp pass outwardly from the separating baffles to discharge through the discharge opening 27, in the nipple 28, at 65 the outer part of the separating chamber,

as also hereinafter more fully explained. These nipples may be termed either discharge or separating nipples, as they enter into the performance of both functions.

The feed baffle or partition 23, and the 70 feed chamber 24, are preferably positioned in the separating member to lead the baffles 20 and the chamber 22, in the path of rotation, so that pulp delivered into the separating chamber will course backwards therein, in the path of rotation during operation. Such arrangement of these parts in the separating members operate with greater efficiency than when arranged otherwise. 75

To assist in more complete separation of 80 the pulp and prevent any considerable part of the finer thereof from being discharged with the coarser parts, I provide a secondary chamber 29, which is preferably positioned outward radially from the separating chamber, with a comparatively small central opening, in the peripheral wall 29 between these two chambers. 85

The separating member preferably terminates in contracted form or funnel shaped in direction outward from the axis, and as illustrated in the drawings, the secondary chamber is best located in the contracted portion. The outer ends of the separating members 11 are provided with screw threaded opening 28', which extend into the secondary chambers through which the nipples 28, are inserted for purposes of assisting separation of the pulp, to the extent desired, as hereinafter explained. The nipples also serve as means for assisting to provide a contracted discharge opening 27, for discharge of separated coarser material. 100

Around the feed opening at the central portion of the receiving member concentrically mounted on the plate 14, as especially illustrated in Fig. 1, I provide a water receiving member 30, with a chamber 31, adapted to connect with radial pipes 32, which pipes at their outer ends are connected with chambers 33, in the respective separating members. These chambers 33, communicate with the secondary chamber, through openings 34, illustrated in Fig. 1. 110

As will be seen, the nipples 28, extend up through the secondary chambers, and are provided at their inner ends with inserted parts 35, Fig. 5, the outer portions of which parts are adapted to enter the openings in the wall between the separating and the secondary chambers, as illustrated in the drawing. The inserted parts 35, are provided with an opening 36, through which the coarser separated material may pass from the separating chamber into the interior bore or chamber 37, of the nipples. 115

The nipples 28, are provided through that portion of their walls which are positioned within the secondary chamber, with suitable openings 38, through which water intro- 120

duced into said secondary chambers by means of the part 30, with its cooperating connections, may pass into the chamber 37, in the nipple and flow in part up through 5 the opening 36, towards the axis, and in part to discharge through the outer openings 27, in the nipples, with the coarser separated material from the separating chamber.

The purpose of this arrangement is to 10 prevent, by resisting inward flow of water through the opening 36, the outward passage of finest substances of the pulp to discharge with the coarser portions passing through the hole 27, thereby effecting a more nearly 15 complete separation of the coarse and fine, the nipples therefore not only serve for purposes of assisting separation through the openings 36, but also as discharge mediums for the coarser material through their openings 27. 20 These nipples with their inserted parts 35, may be unscrewed and removed from the separating members if desired, as illustrated by the removed nipple in Fig. 5.

As shown in the drawings, a launder 39, 25 is formed encircling the rotating parts of the separator. This launder is provided with two annular compartments 40 and 41, respectively, and the compartments have annular slots 42 and 43, opening towards the 30 axis of the separator, which are adapted to receive the materials delivered from the separating chambers through their discharge opening.

To enable the coarser and finer materials 35 to be radially delivered by their respective discharge openings, into the separate and appropriate compartments of the launder, for final discharge from the separator, these 40 discharge openings are positioned a sufficiently short distance apart in direction along the axis, to permit of radial alignment with the annular slots in the launder, so the material discharged will be thrown through such slots and into their appropriate 45 compartments and be separately discharged through the extended end of the launder.

The separator is provided with a feed pipe 44, which is intended, to connect with any suitable source of supply of finely divided 50 and emulsified material or pulp to be separated, and is also intended to be provided with a valve, not shown, for governing the flow of such pulp to the separator. The pipe 44, has a suitable part which passes through the central opening to the receiving member 55 terminating in position to deliver feed of pulp into the receiving chamber of the separator.

As means for supplying water or other 60 liquid for use in the secondary chamber 29, for use in the nipple 28, I provide a water supply pipe 45, which may be connected with any appropriate source of supply of water for this purpose.

65 The pulp feed pipe 44, is supported and

held to place by a stand 46, mounted on the base plate of the separator, as illustrated in Fig. 1.

In operation the separator is rotated at a requisite comparatively high rate of speed 70 to develop sufficient centrifugal force for effecting separation desired, and pulp for separation is introduced into the receiving member through its feed pipe 44, in sufficient quantities to keep the separating chambers full of pulp, and in quantity largely in excess of what will pass through the discharge opening 27, for the coarser parts of material.

The pulp from the receiving member 75 passes through the opening 26, into the feed passage or chamber 24, of the separating member, and is delivered from such passage along the zone of the outer edges of the separating baffles in the separating chamber 19.

The pulp then flows in part, transversely across the outer extremities of the separating baffles and across the openings or spaces between these baffles in a direction backwards to the movement of rotation, such general course being indicated by the arrows in Fig. 2.

During this time the finer parts of the pulp are carried up by the flow of liquid, 80 between and above such baffles towards the axis, and also along backwards in the path of rotation across above the inner edges of such baffles to discharge over the inner edge of the discharge baffle 21, into the discharge chamber 22, for the fine, and from there out of the separating member through the peripheral discharge opening 25, of the discharge chamber, which discharge opening is indicated in dotted lines, and into its appropriate compartment of the launder, for delivery from the separator through the extended portion 47, of the launder. The direction of travel of the rotatable parts of the separator, is indicated by the large arrows in Fig. 2.

As the pulp passes into the separating chamber, and across the outer edges of the separating baffles, as just above explained, the coarser parts are separated and precipitated outward by the action of centrifugal force, and are carried through the opening 36, at the outer part of the separating chamber, into the bore or chamber 37, of the discharge nipple 28, and from there out through the opening 27, in the outer part of the nipple, into its appropriate compartment of the launder, and to final delivery separately from the fine through the extended portion 47, of the launder.

During this operation, water flows into the bore or chamber 37, of the discharge nipples, as has been above explained, in sufficient quantities so that part of such water will pass inwardly towards the axis of rota-

tion through the opening 36, at the inner end of the nipple, and afford sufficient resistance to prevent any substantial amount of the fine part of the pulp which would incidentally flow through these openings to discharge with the coarse, from so passing with the coarse, but however, such flow of water is not intended to be sufficiently strong to prevent the coarser materials from entering the chamber 37, and passing out of the outer end of the nipples.

The amount of water which should be supplied to the chamber 37 of the nipples, depends on the conditions of operation and the material to be separated which in some instances best serves the purpose to be in quantity only to substantially equal the amount of liquid discharged through the outer holes 27 in the nipples.

20 What I regard as new and desire to secure by patent is:

1. In a centrifugal separator, the combination of a rotatable member provided with a chamber adapted to receive pulp for separation, a peripherally diverging separating member thereon, having a separating chamber provided with discharge openings for the respective separated constituents of the pulp, means communicating from the receiving chamber to the separating chamber for flow of pulp to the latter, baffles within the separating chamber positioned transversely to the path of rotation of the receiving member, means for supporting and rotating the receiving and separating members and means for supplying pulp to the receiving chamber, substantially as described.

2. In a centrifugal separator, the combination of a rotatable member provided with a chamber adapted to receive pulp for separation, removable radially diverging open top members mounted thereon, having separating chambers terminating in discharge openings for the respective separated portions of pulp, means communicating from the receiving chamber to the separating chambers for flow of pulp to the latter, baffles within the separating chambers positioned transversely to the course of rotation, means for supporting and rotating the separating and receiving members, and means for supplying pulp to the receiving chamber, substantially as described.

3. In a centrifugal separator, the combination of a rotatable receiving member provided with a chamber adapted to receive pulp for separation, radially diverging open top removable separating members thereon, having separating chambers with openings for discharge of the respective constituents of the separated pulp, baffles within the separating chambers, fixed with respect to the separating members and extending in direction transverse to the path of rotation of such members, means for introducing

pulp to the receiving chambers and means for supporting and rotating the receiving and separating members, substantially as described.

4. In a centrifugal separator, the combination of a rotatable member, provided with a receiving chamber for pulp, a removable peripherally diverging member thereon having a separating chamber provided with a passage for feed of pulp to said chamber in position therein leading in rotation of said member, and a passage for discharge of finer material positioned following said feed passage, in rotation, a separating baffle within said separating chamber positioned therein radially from the axis and transversely to the course of rotation, interposed between said feed passage and discharge passage, means for introducing pulp to the separating member and means for supporting and rotating the receiving and separating members, substantially as described.

5. In a centrifugal separator, the combination of a rotatable member provided with a chamber adapted to receive pulp for separation, peripherally diverging members therefrom, having separating chambers provided with openings for discharge of the respective portions of the separated pulp, and separating chambers provided with feed passages in position at their ends leading in direction of rotation, multiple separating baffles within the separating chambers extending radially from the axis and transversely to the path of rotation of the separating members and positioned behind said feed passage with respect to the direction of rotation, means for introducing pulp to the separating member, and means for rotating the receiving and separating members, substantially as described.

6. In a centrifugal separator, the combination of a rotatable receiving member, provided with a chamber adapted to receive pulp for separation, a separating member having a pulp feed passage thereto, in position leading in direction of rotation, and a discharge passage following in rotation, said separating member provided with a secondary chamber communicating with the separating chamber through a passage adapted to deliver flow of liquid to resist discharge of finer portions of pulp, means for supplying liquid to said secondary chamber irrespective of feed of pulp, means for supporting and rotating the receiving and separating members and means for catching and delivering separately from the separator, the respective separated parts of the separated pulp, substantially as described.

7. In a centrifugal separator, the combination of a rotatable receiving member, provided with a chamber adapted to receive pulp for separation, a separating member

having a pulp feed passage thereto in position leading in direction of rotation and a discharge passage following in direction of rotation and provided with an intermediate 5 separating chamber, multiple radial baffles in the separating chamber extending transversely to the path of rotation, said separating member provided with a secondary chamber communicating with the separating 10 chamber through a passage adapted to deliver flow of liquid resisting discharge of finer portions of pulp with the coarser portions thereof, means for supplying liquid to said secondary chamber irrespective of feed 15 of pulp, means for supporting and rotating the receiving and separating members, and means for catching and delivering separately from the separator the respective separated constituents of the pulp, substantially 20 as described.

8. In a centrifugal separator, the combination of a rotatable receiving member, provided with a chamber adapted to receive pulp for separation, separating members 25 having separating chambers with feed passages thereto, and discharge passages for discharge of the respective parts of the separated material, said separating members provided with secondary chambers communicating 30 with the separating chambers through passages adapted to deliver resisting flow of liquid to discharge of finer portions of pulp, with the coarser portions, a removable separating and discharge member, extending 35 substantially through the secondary chamber, and communicating with the separating chamber, means for supplying liquid to said secondary chamber irrespective of feed of pulp, and means for supporting and 40 rotating the receiving and separating members, substantially as described.

9. In a centrifugal separator, the combination of a rotatable member provided with a receiving chamber adapted to receive pulp 45 for separation, removable peripherally extended separating members, contracting in size in direction outward from the axis of the separator, provided with a separating

chamber and a discharge chamber having 50 openings for separate discharge of the respective parts of the separated pulp, said separating member provided with a secondary chamber positioned outward from the separating chamber, having an opening into said separating chamber and provided with 55 a peripheral opening, a separating and discharge nipple inserted in such peripheral opening, extending through the secondary chamber and communicating with the separating chamber through a comparatively 60 small passage adapted to effect discharge of coarser material from the separating chamber, said nipple provided with a liquid passage through its wall within the secondary chamber, adapted to receive flow of liquid 65 from the secondary chamber, means for introducing liquid into the secondary chamber, and means for rotating the receiving and separating members, substantially as 70 described.

10. In a centrifugal separator, the combination of a rotatable receiving member provided with a chamber adapted to receive pulp for separation, separating members having separating chambers with a pulp feed 75 passage from the receiving chamber thereto positioned to precede the separating chambers in direction of rotation, and a discharge channel for discharge of finer parts of the pulp from the separating chamber following said separating chambers in rotation, multiple baffles in the separating chamber positioned radially outward from the axis of the separator and transversely to the path of rotation and having a passage 80 between their inner edges and the outer periphery of the receiving member, means for introduction of pulp to the receiving member, means for supporting and rotating the receiving and separating members, and 85 means encircling the separating members adapted to catch and deliver separately from the separator, the respective portions of the separated pulp, substantially as described.

WILBUR H. PECK.
